United States Patent Office

Des. 227,073

Patented June 5, 1973

227,073

HANDLE FOR DOORS, DRAWERS, AND THE LIKE

David F. James, Redondo Beach, Calif., assignor to Heyer Hardware Mfg. Co., Anaheim, Calif.

Filed Sept. 10, 1971, Ser. No. 179,604

Term of patent 14 years

Int. Cl. D8—06

U.S. Cl. D8—166

FIG. 1 is a front elevational view of a handle for doors, drawers, and the like, showing my new design;

FIG. 2 is an elevational view of one of the similar sides thereof; and

FIG. 3 is an elevational view of one of the similar ends thereof.

I claim:

The ornamental design for a handle for doors, drawers, and the like, as shown and described.
